GAME PIECE

William J. Weir, Miami, Fla.

Application February 21, 1949, Serial No. 989

Term of patent 14 years

(Cl. D34—5)

To all whom it may concern:

Be it known that I, William J. Weir, a citizen of the United States and resident of Miami, county of Dade, and State of Florida, have invented a new, original, and ornamental Design for a Game Piece, of which the following is a specification, reference being had to the accompanying drawing, forming a part thereof.

In the drawing,

The dominant features of my new design are shown in solid lines in the drawing.

I claim:

The ornamental design for a game piece, as shown and described.

WILLIAM J. WEIR.
